UNITED STATES PATENT OFFICE.

WALTER S. PORTER, OF SAN FRANCISCO, CALIFORNIA, ASSIGNOR OF ONE-HALF TO
LOUIS MAY, OF SAN FRANCISCO, CALIFORNIA.

DENTAL CABINET AND LABORATORY.

1,292,055.

Specification of Letters Patent. Patented Jan. 21, 1919.

Application filed April 25, 1918. Serial No. 231,985.

To all whom it may concern:

Be it known that I, WALTER S. PORTER, a citizen of the United States, residing in the city and county of San Francisco and State of California, have invented a new and useful Improvement in a Dental Cabinet and Laboratory, of which the following is a specification.

My invention relates to improvements in furniture for dental offices and the like wherein a dental cabinet is provided with a laboratory space and drawer units, containing tools and other requirements necessary for the practice of the profession, which operate to inclose and conceal the laboratory when not in use.

The primary object of the present invention is to provide an improved dental cabinet containing a concealable laboratory space wherein laboratory work such as grinding, swaging, polishing and other operations producing debris may be carried on.

Another object of the invention is to provide a cabinet of the character described having extensions which may be used to screen the cabinet and laboratory space when in use and also to serve in conjunction with the cabinet as a partition to divide a room or office into reception and working compartments thereby eliminating the necessity of building a permanent partition.

It is a further object of the present invention to provide a laboratory or working space which may be closed with chests or units of drawers containing drugs and medicines or dental tools readily accessible to the operator and adjacent to the dental chair without exposing the laboratory section or space.

I accomplish these several objects by means of the device disclosed in the drawings forming a part of the present specification wherein like characters of reference are used to designate similar parts throughout the said specification and drawings, and in which—

Figure 1 is a front elevation of the cabinet closed to conceal the laboratory space;

Fig. 2 is an end elevation of Fig. 1;

Fig. 3 is a broken front elevation of the cabinet arranged to disclose and render accessible the laboratory space;

Fig. 4 is a broken plan view of the cabinet; and

Fig. 5 is a vertical sectional view taken on line 5—5 of Fig. 1 in the direction indicated.

Referring to the drawings the numeral 1 is used to designate in general a chest of drawers having a continuous top 2 and an open space 3 for the storing of power units required such as a motor 4 operating an air compressor 5, and a container 6.

The chest of drawers 1 is provided with a vertically disposed back portion 7 having forwardly extending cabinets 8 secured near the top or upper portion of said back portion.

A forwardly extending horizontally disposed shelf 9 is secured to the back portion 7 and end pieces 11 and spaced between the cabinets 8 and the top 2 of the chest of drawers 1 so as to provide a laboratory space A between said shelf 9 and said top 2, within which space A may be mounted laboratory accessories such as a power unit B, vise C, burner D for heating purposes, cement box E, and swaging block G which latter is set flush with the top 2 of the chest of drawers 1, as disclosed in Fig. 5 of the drawings.

Additional drawer units 12 are hingedly mounted as at 14 to the end pieces 11 of the cabinet and are arranged to move over and flush with the front of the chest of drawers 1 and the top of the shelf 9 to inclose the laboratory space A when not in use as disclosed in Figs. 1 and 5 of the drawings.

A flexible electric connection or cord 16 leads from the top 2 of the chest of drawers 1, at a point adjacent one of the end pieces 11, to one of the additional drawer units 12, as disclosed in Figs. 3 and 4 of the drawings, to connections on a suitable electrical switch-board 17 secured to the front central corner of one of the additional drawer units 12.

Doors 19 are hingedly mounted upon the front of the chest of drawers 1 to inclose the front of said chest and the space 3 therein.

Vertically disposed extensions 21 are slidably mounted upon the back of the back portion 7 and are arranged to be extended beyond the ends of the cabinet as disclosed in Figs. 3 and 4 of the drawings, so that said cabinet and extensions 21 when extended may be used as a partition to screen the laboratory and also to serve as a partition between a reception compartment and

a working compartment within the same room thereby screening patients within the dental chair from others awaiting their turn in the reception compartment or section of 5 the room.

When the cabinet is in closed form as disclosed in Fig. 1 of the drawings all of the drawers in the entire cabinet containing 10 tools and dental instruments are readily accessible to the dentist or operator and adjacent to the operating chair, when the doors 15 are opened.

If any laboratory work should suddenly become necessary the operator will not be 15 required to go into another room or use another room for such laboratory work but by moving the additional drawer units 12 away from the shelf 9 and the top 2 of the 20 chest of drawers 1 he exposes and renders accessible the laboratory space A, as disclosed in Figs. 3 and 4 of the drawings. When through with such work the units 12 may be again moved flush with the front of the chest of drawers 1 and the shelf 9 to 25 again conceal the laboratory space A.

Having thus described my invention what I claim as new and desire to secure by Letters Patent is—

1. In an article of manufacture, a dental 30 cabinet and laboratory comprising a chest of drawers having a continuous top and an open space under the top for power units; a back portion extending upward from the chest of drawers; a horizontally disposed 35 shelf extending forward from the back portion and spaced above the chest of drawers to form a space for laboratory tools and accessories; and additional chests of drawers mounted to move flush with the top of the 40 shelf and the front of the first named chest of drawers to inclose the space under the

shelf and to move away from said first named chest of drawers and shelf to render the laboratory space accessible; and vertically disposed extensions slidably mounted 45 on the back of the first named chest of drawers and the back portion to move beyond the ends of the cabinet to screen the laboratory space when exposed.

2. In an article of manufacture, a dental 50 cabinet and laboratory comprising a chest of drawers having a continuous top and a centrally disposed open space beneath said top for the reception of power units; doors mounted to inclose the space and the 55 drawers; a back portion extending above the top of the chest of drawers; forwardly extending cabinets mounted upon the upper portion of the back portion; a forwardly extending horizontally disposed shelf mounted 60 upon the back portion and spaced between the cabinets and the chest of drawers to provide a laboratory space between said shelf and chest of drawers; suitable dental accessories mounted within the space; and additional drawer units hingedly mounted above the first named chest of drawers and on each 65 end thereof to swing flush with the front of the first named chest of drawers and with the top of the shelf to inclose the laboratory 70 space and provide a continuous plane with the shelf and to swing away from said shelf and drawers to render the laboratory space accessible; and vertically disposed extensions slidably mounted upon the back of the 75 first named chest of drawers and back portion rising therefrom to move beyond the ends of the said first named chest of drawers to screen the laboratory space and cabinet.

In witness whereof I hereunto set my signature.

DR. WALTER S. PORTER.
